(57) **CLAIM**

The ornamental design for a display screen or portion thereof with a graphical user interface, as shown and described.

DESCRIPTION

FIG. 1 is an embodiment of a display screen or portion thereof with a graphical user interface.

FIG. 2 is a front enlarged view of a portion of the embodiment of FIG. 1 (denoted in that figure with reference number 2).

FIG. 3 is another embodiment of a display screen or portion thereof with a graphical user interface; and,

FIG. 4 is a front enlarged view of a portion of the embodiment of FIG. 3 (denoted in that figure with reference number 4).

The dash-dot broken lines show the display screen or portion thereof and form no part of the claimed design. The dash-dot broken lines in the figures denote portions of the display screen or portion thereof with a graphical user interface that form no part of the claimed design.

1 Claim, 4 Drawing Sheets
